H. M. Plaisted,

ATTORNEY.

UNITED STATES PATENT OFFICE

MORRIS NUDELMAN, OF ST. LOUIS COUNTY, MISSOURI

WHIRLING TOY

Application filed February 3, 1930. Serial No. 425,532.

This invention relates to certain new and useful improvements in whirling toys, the peculiarities of which will be hereinafter fully described and claimed.

The main objects of my invention are first, to provide an improved whirligig; secondly, to provide a manually twisted multiple cord for said whirligig adapted to produce a humming, whistling or musical sound thereby; thirdly, to provide two colors thereon adapted to display a third color when blended by whirling; and fourthly, to produce a rattling accompaniment to said sounds.

In the accompanying drawings in which like reference numerals indicate corresponding parts,

Fig. 1 represents a perspective view of my device;

Fig. 2, an outside face view of one side member of my whirligig;

Fig. 3, an inside view of the other side member; and

Fig. 4, a center sectional view of the two members as assembled.

My device belongs to the class of whirling toys that are supported by the hands and manually operated to produce a whirling motion upon a whirligig by alternately tensioning and slackening a multiple cord supporting said whirligig.

Referring to the drawings, the numerals 1 designate two rings adapted for insertion of a finger on each hand. These rings thus manually spaced apart are connected by a multiple cord of two or more strands 2—2. Intermediately located between said rings, preferably midway on said multiple cord is mounted a disc, preferably hollow. This disc has holes located on a diameter of the disc and equidistant from its center through which the strands of said cord pass as shown in Fig. 1 and separate them somewhat, so that by swinging said disc on the cord held loosely, the cord will become twisted oppositely in the sections on each side of the disc.

By manual tension on the twisted cord, rotation will be given to the disc as the twisted cord unwinds. The weight of the disc causes it to twist the sections of the cord again in reverse directions in the respective

sections, and by again applying tension to the cord the disc will whirl reversely at high speed. Thus by alternately tensioning and slackening the supporting cord, the disc will continue whirling in alternate directions.

My improved form of disc consists of a flat circular side member 3 having a flange 4 adapted to fit over a flange of smaller diameter 5 on the opposite side member 6 that spaces the sides apart, as shown in Fig. 4. This double flange increases the weight at the periphery of the disc and improves the whirling motion.

In the side faces of one or both of these flanged members are formed openings which will produce a whistling, humming or musical sound when the whirligig is rapidly rotated in either direction. Such openings may be circular as at 7 or they may be of other form and are preferably struck up and bent outward so as to form reeds 8 radially mounted on the disc face and integral or otherwise with the face of each member. I have also shown a rectangular opening 9 provided with double reeds 10 circumferentially located as shown in Fig. 2. The said reed may be of other material than that of the disc members if desired.

For adding to the appearance of this whirligig I provide portions on each face bearing two opposite colors such as blue on the segment 11 and yellow on the segment 12 of the face as indicated in Fig. 2. These two primary colors, for example, will be blended when the device is rapidly rotated, and will display a continuous ring of green color. Other colors may be used.

The said inner flange 5 or other portion of the disc 6, is provided with corrugations 13 forming an irregular inner surface as shown in Fig. 3. One or more balls 14 preferably metallic, are located in my hollow disc and when impinging on said corrugations under rapid rotation of the disc, a continuous rattling sound will be produced which contrasts with the wind sounds of the openings before described and serves as an accompaniment to such sounds.

By making the reeds 8' longer than the reed 8 I produce a different vibration and tone as

regards these two forms, which can be made to harmonize and improve the quality of the resulting wind sound when the whirligig is rotating.

5 I claim:

1. A whirling toy comprising a hollow disc consisting of two flat circular sides and overlapped flanges spacing them apart and affording weight to the periphery,—the inner 10 flange being corrugated and the sides having diametrically spaced matching holes, a double cord passing through said holes for manual operation, and a metallic ball loosely disposed in the space between said sides and 15 flanges and adapted to impinge successively the said corrugations under rotation of the disc, substantially as described.

2. A whirling toy comprising a hollow disc consisting of two flat circular sides having 20 flanges extending from said sides of different diameter and similar width, the smooth outer flange fitting over the inner flange, the inner flange spacing the sides apart and being corrugated, and the sides having portions struck 25 up forming openings with reed edges integral therewith and having diametrical matching holes, a double cord disposed in said holes for manual operation, and a ball loosely disposed in the spaces between said sides adapted to 30 rattle around the said corrugations under rotation of the disc, substantially as described.

In testimony whereof I have affixed my signature.
